UNITED STATES PATENT OFFICE

JAMES F. MCINTIRE, OF DETROIT, MICHIGAN, ASSIGNOR TO UNITED STATES RADIATOR CORPORATION, OF DETROIT, MICHIGAN, A CORPORATION OF MICHIGAN

DESIGN FOR A RADIATOR

Application filed November 10, 1930. Serial No. 37,604. Term of patent 14 years.

To all whom it may concern:

Be it known that I, JAMES F. MCINTIRE, a citizen of the United States of America, residing at Detroit, in the county of Wayne and State of Michigan, have invented certain new, original, and ornamental Design for a Radiator, of which the following is a specification, reference being had therein to the accompanying drawings, forming a part thereof, wherein:

Figure 1 is a side elevational view of a radiator showing my new design.

Figure 2 is an end elevational view thereof.

Figure 3 is a foreshortened perspective view of a radiator showing the invention.

Figure 4 is a fragmentary top plan view of the radiator; and

Figure 5 is a fragmentary sectional view through the radiator.

The dominant feature of my new design is the portions arranged in different planes in the surfaces of the sections, which portions cooperate when the sections are assembled in a single unit, to provide a series of panels in the side of the unit surrounded by a continuous border.

I claim:

The ornamental design for a radiator substantially as shown and described.

JAMES F. MCINTIRE.
